NECKTIE

Harry A. Clark, Detroit, Mich.

Original application February 26, 1936, Serial No. 65,831. Divided and this application October 25, 1937, Serial No. 170,804

8 Claims. (Cl. 2—154)

This invention relates to neckties, and in particular to neckties simulating bow ties including means for securing neckties in a predetermined position in relation to the collar or shirt with 5 which they are worn.

The ordinary bow tie, whether hand tied or pre-tied, when secured to or around the neckband of a shirt interferes with the outwardly depending front tabs of the usual turn down collar secured to or worn with the shirt. If the collar is well starched, the wings or loops of the tie are forced out of their normal position by being urged outward from the knot portion during wear which causes an appearance of slovenly 10 dress. However, if the wings or loops of the tie are stiffer than the outwardly depending front tabs of the usual turn down collar, the collar becomes wrinkled during wear thereby causing a sacrifice of neatness of dress.

One object of this invention is to provide a necktie which will not interfere with the outwardly depending front tabs of the usual turn down collar.

Another object of this invention is to provide a necktie having novel means for securing the same in inclined relationship to the neckband of the collar or shirt with which it is worn.

Another object of this invention is to provide a necktie having novel means for securing the same in a predetermined relationship to the neckband of the collar or shirt with which it is worn and which will not be distorted from its normal position while being worn by interference from the outwardly depending front tabs of the usual 30 turn down collar.

Another object of this invention is to provide a necktie pre-formed to a desired shape and capable of being held in inclined relationship to the neckband of the collar and shirt with which 35 it is worn.

Another object of this invention is to provide a pre-formed necktie capable of being secured around the neckband of a collar or shirt and held in the desired inclined relationship to the 40 said neckband and spaced laterally central to the collar button.

Another object of this invention is to provide a light weight moulded simulation of a necktie in which essential strength is provided where 45 required for stiffness, and in which unnecessary weight is eliminated for flexibility at the outer depending portions of the wings thereof.

Another object of this invention is to provide a pre-formed necktie capable of being held in 50 inclined relationship to the neckband of the col-

lar or shirt with which it is worn and having removable initialling or advertising medium in connection therewith.

Other objects of this invention will become apparent by reference to the following detailed description taken in connection with the accompanying drawing, in which:

Fig. 1 is a view in elevation showing a necktie embodying the invention positioned in a desired relationship with respect to a turn down collar. 10

Fig. 2 is a cross sectional view taken on the line 2—2 of Fig. 1 looking in the direction indicated by the arrows.

Fig. 3 is an enlarged sectional view taken on the line 3—3 of Fig. 1 normal to the plane of 15 the central portion thereof.

Fig. 4 is a fragmentary rear view in elevation of the knot portion of the embodiment of the invention shown in Figs. 1, 2 and 3 illustrating means for securing the necktie to the collar or 20 shirt with which it is worn together with novel means for maintaining the said necktie in the desired lateral position relative thereto.

Fig. 5 is an enlarged sectional view taken on the lines 5—5 of Fig. 3 looking in the direction 25 indicated by the arrows.

Figs. 6, 7 and 8 are views similar to Figs. 4, 5 and 2 respectively showing how the means for securing the necktie to the collar or shirt with which it is worn is formed to also provide the 30 means for maintaining the said necktie in the desired lateral and inclined position relative thereto whereby the weight of the said necktie may be materially reduced and the said necktie 35 may be more readily covered with fabric if it is so desired.

Although this invention has been disclosed in the drawing and is described herein in particular reference to bow ties or a simulation of bow ties of moulded material, it is not intended 40 to be so limited inasmuch as the invention is equally applicable to four-in-hand ties and to both bow ties and four-in-hand ties constructed with a partial or complete moulded foundation covered with suitable fabric material without 45 departing from the spirit hereof.

This application is a division of my application for Patent Serial No. 65,831, filed February 26, 1936, entitled "Necktie", and issued on Mar. 29, 1938, as Patent No. 2,112,437.

Referring particularly to the drawing wherein like numerals refer to like and corresponding parts throughout the several views, the embodiment of the invention shown in Figs. 1 to 5 inclusive comprises a necktie having a central 55

knot portion 20 and a pair of wings 21, which, in the particular construction disclosed, are preferably moulded of a light weight flexible material such as rubber of a low specific gravity 5 or sponge rubber. Any suitable material may be used and numerous shapes and designs may be adopted, all within the scope of the invention. In order that the necktie may be extremely light yet strong and flexible, the wings 21 there- 10 of are divided into a solid top portion 22 and double depending wing tips 23. The solid top portion 22 of each wing 21 is decreased in depth toward the extreme outside top end of each wing as best illustrated by the dotted lines 24 in Fig. 1. 15 The dot and dash lines 25 in Figs. 1 and 3 designate a typical turn down collar, the knot portion 20 and the wings 21 of the necktie construction being shown in a preferred relationship to the said typical turn down collar 25.

20 The central knot portion 20 and the wings 21 are maintained in a desired inclined spaced relationship to the vertically disposed neckband 26 of the shirt or collar with which the necktie is worn by means of the triangular block 41 preferably moulded integral with the said central knot portion 20 of the necktie as best illustrated in Fig. 2.

25 By referring to Figs. 3, 4, and 5 it will be observed that the triangular block 41 is narrower at the top than at the bottom so that it will not interfere with the outwardly depending front tabs of a typical turn down collar, and, that a recess 42 has been provided in the rear of the said triangular block 41 to receive the collar button 38 when the necktie is held tightly against the vertically disposed neckband 26 of a shirt or collar with which the said necktie is worn, see Fig. 3.

30 A means for securing the knot portion of the necktie shown in Figs. 1 to 5 inclusive against the vertically disposed neckband 26 of a shirt or collar with which the necktie is worn is best illustrated in Figs. 4 and 5, and comprises an anchorage 43 moulded in a suitable position in the triangular block 41 having ends 44 and 45 there- 35 of protruding therefrom. The end 44 of the said anchorage 43 has an aperture 46 therein through which is looped and secured one end of an elastic securing band 47 having a hook 48 at the other end thereof adapted to readily engage the conveniently disposed opposite protruding end 45 of the said anchorage 43 through a suitably located aperture 49 therein. The length and tension of the elastic securing band 47 may be adjusted by the usual sliding buckle 50 suitably fastened to one end of the said securing band 47.

35 It is therefore apparent by reference to Fig. 3 that the necktie may be readily secured against the vertically disposed neckband 26 of a collar or shirt with which it is worn by first positioning the triangular block 41 central with and over the collar button 38 in such a manner that the said collar button 38 is positioned in the recess 42 of the said triangular block 41, and then fastening the elastic securing band 47 around the said vertically disposed neckband 26 in tensional relation thereto. When the knot portion 20 of the necktie is automatically held in inclined relationship to the neckband 26 of a collar or shirt by the triangular inclined block 41, the wing portions of the necktie in no manner interfere with the outwardly depending front tabs of the typical turn down collar illustrated by the dot and dash lines 25 of Fig. 3. The said triangular inclined block 41 automatically centers the central knot portion

20 of the necktie between the said outwardly depending front tabs 25.

An ornamental initial or advertising disk 51 having a male fastener ball member 52 at the center of the rear thereof may be removably snapped into engagement with a cooperating female snap fastener fitting 53 moulded in the center of the knot portion 20 of the necktie at the base of a suitable disk receiving depression 54 therein. Initials or advertisements may be moulded directly in the knot or wing portions of the necktie, however, it is found to be most economical to mould neckties with a snap fastener fitting therein whereby any number of different initials or advertisements may be applied thereto without altering standard production moulds.

The alternate construction shown in Figs. 6, 7 and 8 is identical to the construction shown in Figs. 4, 5 and 2 respectively except that the triangular block 41 at the rear of the central knot portion 20 of the necktie shown in Figs. 1 to 5 inclusive has been eliminated and an anchorage 430 has been moulded in the central knot portion 20 of the necktie which performs the combined function of the said triangular block 41 of the necktie shown in Figs. 1 to 5 inclusive and the anchorage 43 thereof for which the said anchorage 430 was substituted.

The said anchorage 430 moulded in the central knot portion 20 of the necktie has the rearwardly projecting sides 410 thereof formed with respect to the anchorage embedded in the said central portion 20 of the necktie to hold the said necktie inclined with respect to the neckband of the collar with which the necktie is worn. The said rearwardly projecting sides 410 of the said anchorage 430 are also formed to provide a pair of oppositely sloping surfaces 4100 adapted to operate with the outwardly depending front tabs 25 of a typical turn down collar to center the said central knot portion 20 with respect to the said outwardly depending front tabs 25. The said anchorage 430 is provided with laterally projecting ends 440 and 450 as best indicated in Figs. 6 and 7. The end 440 of the said anchorage 430 has an aperture 460 therein through which is looped and secured to one end of an elastic securing band 47 having a hook 48 at the other end thereof adapted to readily engage the conveniently disposed opposite protruding end 450 of the said anchorage 430 through a suitable located aperture 490 therein. The length and tension of the elastic securing band 47 may be adjusted by the usual sliding buckle 50 suitably fastened to one end of the said securing band 47. The rear surfaces of the said laterally projection ends 440 and 450 of the said anchorage 430 bear against the collar band of the collar with which the necktie is worn. The collar button of the shirt or collar with which the necktie is worn is positioned in the recess 420 between the said laterally projecting ends 440 and 450 of the said anchorage 430.

It is readily observed that a necktie constructed in accordance with the disclosure of Figs. 6, 7 and 8 will function precisely the same as a necktie constructed in accordance with the disclosure in Figs. 1 to 5 inclusive, however, in certain instances, as for example, when a moulded necktie is to be covered with a fabric, the construction shown in Figs. 6, 7 and 8 is preferable inasmuch as the difficulty of neatly covering the bulky triangular block 41 is avoided. Also, the construction shown in Figs. 6, 7 and 8 is considerably lighter than the construction shown in Figs. 1 to 5 in-

clusive and, in certain instances, is preferred because of the lightness thereof.

Although but two specific embodiments of this invention have been shown and described herein, it will be understood that various changes including the size, shape, arrangement and detail of the parts thereof may be made without departing from the spirit of the invention and it is not intended to limit the scope thereof other than by the terms of the appended claims.

I claim:

1. In a moulded necktie having a central knot portion, in combination, a triangular block on the rear of said central knot portion for holding the said necktie in inclined relationship to the vertical neckband of a collar with which it is worn, the front of said knot portion having a depression formed therein, an initialing disk, means for securing said initialing disk to the said knot portion at the base of said depression therein, and means for securing said necktie to said vertical neckband.

2. In a moulded necktie having a central knot portion, in combination, a triangular block on the rear of said central knot portion for holding the said necktie in inclined relationship to the vertical neckband of a collar with which it is worn, the rearwardly disposed portion of said triangular block having a depression formed therein for receiving the collar button of the said collar, the upper portion of the said triangular block being beveled to adapt the same for insertion laterally between the outwardly depending tabs of the usual turn down collar, the front of said knot portion having a depression formed therein, an initialing disk, means for securing said initialing disk to the said knot portion at the base of said depression therein, and means for securing said necktie to said vertical neckband.

3. In a necktie having a moulded central knot portion, means at the rear of the said central knot portion adapted to hold the bottom of the said central knot portion inclined outwardly with respect to the vertical neckband of a collar with which the said necktie is worn, the said inclining means having upwardly and inwardly sloping sides adapted to be positioned between the outwardly depending tabs of the said collar whereby to cooperate with the said tabs and hold the said necktie against rotation on an axis normal to the said collar band, and means for securing said necktie to the said vertical neckband.

4. In a necktie having a moulded central knot portion, a block at the rear of the said central knot portion having the bottom thereof thicker than the top thereof which holds the bottom of the said central knot portion inclined outwardly with respect to the vertical neckband of a collar with which the said necktie is worn, the said block having upwardly and inwardly sloping sides adapted to be positioned between the outwardly depending tabs of the said collar whereby to cooperate with the said tabs and hold the said necktie against rotation on an axis normal with respect to the said collar band, and means for securing the said necktie to the said vertical neckband.

5. In a necktie having a moulded central knot

portion, in combination, means at the rear of the said central knot portion adapted to hold the bottom of the said central knot portion inclined outwardly with respect to the vertical neckband of a collar with which the said necktie is worn, the said inclining means having upwardly and inwardly sloping sides adapted to be positioned between the outwardly depending tabs of the said collar whereby to cooperate with the said tabs and hold the said necktie against rotation on an axis normal to the said collar band, the front of the said central knot portion having a depression formed therein, an initialing disk, means for securing said initialing disk to said central knot portion at the base of the said depression therein, and means for securing the said necktie to said vertical neckband.

6. In a necktie having a moulded central knot portion, in combination, a block at the rear of the said central knot portion having the bottom thereof thicker than the top thereof which holds the bottom of the said central knot portion inclined outwardly with respect to the vertical neckband of a collar with which the said necktie is worn, the said block having upwardly and inwardly sloping sides adapted to be positioned between the outwardly depending tabs of the said collar whereby to cooperate with the said tabs and hold the said necktie against rotation on an axis normal with respect to the said collar band, the front of the said central knot portion having a depression formed therein, an initialing disk, means for securing said initialing disk to said central knot portion at the base of the said depression therein, and means for securing the said necktie to the said vertical neckband.

7. In a necktie having a moulded central knot portion, in combination, means at the rear of the said central knot portion adapted to hold the bottom of the said central knot portion inclined outwardly with respect to the vertical neckband of a collar with which the said necktie is worn, the said inclining means having upwardly and inwardly sloping sides adapted to be positioned between the outwardly depending tabs of the said collar whereby to cooperate with the said tabs and hold the said necktie against rotation on an axis normal to the said collar band, initialing means, and means embedded in said central knot portion for securing said initialing means thereto, and means for securing the said necktie to said vertical neckband.

8. In a necktie having a moulded central knot portion, in combination, means at the rear of the said central knot portion adapted to hold the bottom of the said central knot portion inclined outwardly with respect to the vertical neckband of a collar with which the said necktie is worn, the said inclining means having upwardly and inwardly sloping sides adapted to be positioned between the outwardly depending tabs of the said collar whereby to cooperate with the said tabs and hold the said necktie against rotation on an axis normal to the said collar band, initialing means on the face of the said central knot portion, and means for securing said necktie to said vertical neckband.

HARRY A. CLARK.
